UNITED STATES PATENT OFFICE.

WILLIAM J. KENNEDY, OF POTTSVILLE, PENNSYLVANIA.

DESIGN FOR A STOVE-LID LIFTER.

SPECIFICATION forming part of Design No. 33,147, dated August 28, 1900.

Application filed July 26, 1900. Serial No. 24,946. Term of patent 7 years.

To all whom it may concern:

Be it known that I, WILLIAM J. KENNEDY, a citizen of the United States, residing at Pottsville, in the county of Schuylkill and State of Pennsylvania, have invented and produced a certain new and original Design for a Stove-Lid Lifter; and I do declare the following to be a full, clear, and exact description of the invention, such as will enable others skilled in the art to which it appertains to make and use the same.

The invention relates to a new and original design for a stove-lid lifter; and it consists of a design of the shape and configuration shown in the accompanying drawing, in which I have illustrated the invention in perspective.

The leading feature of the design consists of the back 1, having a handle 2, a lifter-hook 3, and brush-tufts 4.

What I claim is—

The design for a stove-lid lifter as herein shown and described.

In testimony whereof I have hereunto set my hand in presence of two subscribing witnesses.

WILLIAM J. KENNEDY.
